1,925,705

FILING SYSTEM AND MEANS

Virgil Edwin Robinson, Los Angeles, Calif.

Application March 27, 1928. Serial No. 265,085

21 Claims. (Cl. 129—16.1)

This invention relates broadly to index systems and means therefor, and means therefor, and more particularly to a system which will automatically select and arrange data.

5 The device may, in one embodiment, contemplate the use of cards bearing certain indicia such as an index member or letter and which cards can be dropped at random into a drawer without any attention being given to the relative position of any card to another and still be accessible instantly by classes, or if desired to have only one card in any given class then that one card would be capable of being chosen.

10 The invention has for an object the provision of a system and means which will rapidly, accurately and automatically select data desired without the necessity of an individual search for such data.

15 Another object is the provision of a selective system and means adapted to handle a large number of cards or the like and in such a manner that any one of said cards or group thereof may be readily secured without the necessity of fingering through said cards.

20 25 In practicing the invention, I may provide a drawer adapted to be received within a suitable case or housing and which drawer is adapted to contain one or more cards. These cards may be given letters or numbers, which numbers or letters would be for the purpose of identification as to certain data to be contained upon such cards. The case or housing carries a selector system which may be operated to select any card within the drawer. In brief, the selector system will 30 include various buttons or other operative means which work in conjunction with certain elements carried by the cards whereby the selected cards may be lifted or raised from those cards not desired.

35 40 The invention has for a further object the provision of a system and means of filing cards, as well as the selecting of said cards which is simple as to operation, fool-proof and accurate in use, and generally superior.

45 50 Another object is the provision of a system of selecting data which selects said data directly from a group of adjoining data and in such a manner that the adjoining data are not disturbed.

55 Other objects will appear as the specification proceeds and with the above named objects and others in view, the invention consists in the novel and useful provision, formation, construction, association and relative arrangement of parts, members and features, all as shown in a

certain embodiment in the accompanying drawings, described generally, and more particularly pointed out in the claims.

In the drawings:

Figure 1 is a perspective view of a case or 60 housing and drawer therein, the parts of which housing carry a certain embodiment of the invention,

Figure 2 is a longitudinal sectional view of the 65 housing and drawer and showing certain mechanism of the invention,

Figure 3 is a transverse sectional view of the 70 casing and drawer and selector mechanism, the drawer being in one position,

Figure 4 is a view similar to Figure 3, the drawer 75 being in a raised position,

Figure 5 is a perspective view of an index tab used in practicing the invention,

Figure 6 is a transverse sectional view showing 75 certain steps in the operation of the invention,

Figures 7 and 8 are fragmentary transverse 80 sectional views illustrating further details of the operation of the invention,

Figure 9 is a fragmentary sectional plan view 85 showing the selector mechanism,

Figure 10 is a longitudinal vertical sectional view of the selector mechanism on an enlarged scale from the showing of Figure 2,

Figure 11 is a vertical cross-sectional view on 90 the line 11—11 of Figure 10,

Figure 12 is a transverse sectional view of one 95 of the selector mechanism members, and

Figure 13 is a perspective view of the members 100 shown in Figure 12, the same being spread apart to show features of construction.

Corresponding parts in the several figures are 105 designated by the same reference characters.

Referring now with particularity to the drawings, the improved device is designated as an 110 entirely by A, and the same includes a suitable case or housing a adapted to hold a drawer b. Selector mechanism designated generally as c is carried by the case or housing a and said selector mechanism includes selector bars d, selector bar control means e, and means f for actuating the selector bar control means and for locking said control means in a given position. Means g is adapted to be carried by one or more cards or the like h and the means g is adapted to cooperate with the selector bars d in the selecting of one or more cards h. All of the elements just enumerated are utilized in practicing one embodiment of the invention A.

Any type of drawer b may be utilized and in fact an ordinary type of filing box might be used,

although it is evident that said box would have to cooperate with the selector means *c*. The selector means *c* will first be described in detail, followed by a description of the mechanism or device with which said selector means cooperates in performing a selecting operation. The case or housing may be provided upon its fronting portion with a plate 1 from which project selector buttons 2. These selector buttons are arranged in pairs, as shown at 3 and 4, and may bear certain indicia such as shown in certain of the figures. In the present instance, the selector buttons would be numbered, each pair as 3 and 4 bearing like indicia, as 1—1, 2—2, etc. (see Figure 4). These selector buttons are mounted upon stems 5 which stems carry at their inner ends catches 6. Each catch is provided with a beveled nose 7. The catch is likewise provided with a cut-out portion 8. It will be noted that the plate 1 is bent so as to provide a casing designated generally as 9 for carrying the stems 5, the casing to this end being bored with the stems passed therethrough. Likewise a coil spring 11 is provided for each stem and which coil spring normally urges the stem in an outward direction, that is, outward from the plate 1. In this regard, it will be noted that the coil spring is confined at one end by a wall 12 of the casing 9 and by a member 13 secured to the stem. Adapted to transversely extend between the sides of the case or housing and hinged thereto is a latch 14 constituting a part of the means *f*. This latch may comprise a plate provided with a depending flange 15 and which plate is pivoted or otherwise hinged to the said casing. The flange 15 is adapted to be received in the cut-out portion 8 of any one of the catches 6 when the stem is pushed a certain distance inwardly, as shown in Figure 2. Enclosed within a portion of the casing 9 is one or more of the selector bar control means *e*. The selector bar control means are mounted between bracket members 16 and 17, the bracket members being secured to the casing 9 and the means *e* are mounted in angularly related pairs, as shown at 18 and 19. Taking one of the said means *e* and referring to Figure 13, it will be seen that the same includes two side plates 20 and 21 which are spaced apart. The plate 21 is provided with an elongated channel portion 22 formed by striking the metal outwardly, and with a portion 23 connecting with the channel 22 and substantially at right-angles thereto. This part 23 is formed with a sloping or inclined wall 24 communicating with the bottom of the channel. The side 20 is provided with channels 25, 26, 27 and 28, which are formed by stamping the metal. The channel 26 runs substantially longitudinally of the plate 20 and the channel 25 is at right angles thereto and provided with an inclined wall 29. The channel 27 curves upwardly from the channel 26 to where it meets the channel 28 and the channel 28 is provided with a sloping wall 30. It will be noted that the channel 28 and the channel 26 are substantially parallel. When the plates 20 and 21 are folded so as to be substantially parallel and spaced apart, the general appearance of the means *e* will be as that shown in Figures 11 and 12. The split ends 31 and 32 of the plates may be secured together in any approved manner. It will be observed at this time that the rear part of the casing or housing carries a casing 33, the same comprising two spaced-apart substantially parallel plates 34 and 35, which are secured to

the housing in any approved manner, such as shown at 36 and between which plates are means *e* identical in construction with the means carried between the plates 16 and 17. We, therefore, have means *e* for both the front and rear portion of the casing, and each pair of means, such as 37 and 38 (see Figure 9) would be so mounted as to correspond to the members 18 and 19; in other words, in the same angular relation.

Adapted to be confined as between members 20 and 21 are pins 39 and which pins are flattened at one end 40 for the purpose of securing said ends to the selector bars *d*. The pins 39 are formed with transverse bores 41 through which bores are passed slide dogs 42. The forward means *e* is so arranged that the pin 39 therefor is movably held at its upper end within a member 13 carried by a stem 5. The lower end of said pin 39 is connected to the bar *d*. The arrangement is such that the two members *e*, both front and rear, which are in parallelism, have pins passed therethrough which connect with the same bar *d*. The bars *d* are identically formed and are right-angular in cross-section, as shown at 44. In this particular, each group of said 100 bars which would comprise two thereof, are so arranged that the lower portions, which may be termed flanges 45, face each other.

The cards *h* carry means *g*, as shown in Figure 5. The means *g* includes a base portion 46 provided with a part 47 bent at an angle to the base portion and with a shank or stem 48 which terminates in an arrow-shaped head 49, in that the head has parts extending outwardly from the sides of the stem or shank, as shown at 50 and 51. The cards at various positions, depending upon the index number selected, would be slotted near the top edge thereof and the member 47 passed through said slot, then bent so as to engage a surface of the card, the card being confined between the parts 46 and 47. The appearance of the card would be similar to that shown in Figures 3 and 4.

The case or housing is provided with means *j* for raising the drawer relative to the base of said housing. This means in the present instance, comprises an elongated lever arm 52 terminating in a crank-handle portion 53 and which lever arm consists of a plate which is adapted to be rotated against a flat plate 54 carried on the bottom surface of the drawer *b*. Thus upon rotating the handle 53 so as to swing the lever arm from the position of Figure 3 to that of Figure 4, the drawer will be lifted upwardly, as shown.

As is customary, a follower block 55 may be within the drawer and movable to selected positions through the medium of the screw-shaft 56 operated by handle 56a.

The operation, uses, and advantages of the invention are as follows:

In the normal position, the selector buttons 2 would all extend outwardly the same distance from the front of the case, as shown in Figure 1, and these buttons are arranged in pairs with suitable indicia appearing upon the surface thereof. In the present instance, the buttons are numbered as shown in Figure 4, both buttons of each pair being given like numbers. The particular system of indicia shown on the buttons in the drawings is arbitrary, as any other indicia would be equally satisfactory, depending upon use of the invention. It is supposed that the drawer has been filled with cards and that the cards are numbered, as shown at 60, and likewise certain thereof given an index letter 61. If

the numbers extend from "0" to "9", there will be ten pairs of buttons. The card or cards would be subdivided to correspond to the number of buttons, as shown at 62. Each data card would be 5 divided by printing or otherwise into as many vertical columns as there are bars or buttons and the tabs projecting beyond the edges of the cards would, therefore, be in horizontal zones, said zones being parallel to the drawer sides and the 10 heads of each of these tabs which are in any of said horizontal zones will be, in this instance, in one of three possible vertical positions so as to divide each of said horizontal zones into three parts or subzones, one above the other, but all 15 within the above horizontal zone. Depending upon the system, indicia cards might have as many vertical columns as there are buttons instead of pairs of buttons, in which case only one button of a pair would be used at a time in the 20 operation of the selector mechanism. Suppose the cards placed in the drawer run from 1 to 1000, and card 271 is to be selected. This card would first have secured thereto certain of the means *g*, as shown in Figures 3, 4, 6, 7, and 8. Referring to 25 Figures 6, 7, and 8, the means *g* would be secured to the card in the following manner: Three of the means *g* will be used, located in columns 2, 7, and 1 of the card, as shown at 62^a, 63 and 64. It will be observed that the heads of the 30 means *g* are spaced at different heights relative to the top edge of the cards. This may be accomplished by providing the means *g* all of a given length or height, and spacing them at different heights by their connection with the card or cards or providing different lengths of the means *g*. The assembling of the means *g* with respect to the card 271 would be as follows: The number 2 means *g* would have its head closest to the top edge of the card, the number 7 means *g* 40 would be placed one notch higher than the head number 2, and the means *g* numbered 1 would be two spaces above the top edge of the card or one space above the number 7 head. This is clearly illustrated in the figures. The first step 45 in the selection of this card would be to revolve the handle 53 to lift the drawer and the drawer will be moved from the position shown in Figure 3 to that of Figure 4. Where the numbers are not 50 similar, such as two "ones" coming together, it is preferable to press both buttons of a pair. In this instance, the pair of No. 2 buttons would be pushed inwardly. Due to the angular relation that exists between the means *e*, the bars *d* would be caused to approach, as shown in Figure 9. 55 When the buttons are pushed inwardly, the nose portions 7 thereof will lift the member 14 and cause the latch to be received within the catch or slots 8 and to hold said buttons in their inward position. It will be noted that each of the 60 slide dogs 42 of the means *e* will slide along or within the channel or groove 22 into the channel 23 where it will contact with the inclined wall 24 and move said dog into the channel 25 and downward to the channel 26. The pair of buttons No. 7 are next pressed and the nose will lift the latch and release the latch from the catch of the buttons No. 2, and permit the buttons to again assume a normal outward position. There is, however, a slight lag in the movement of the 65 bars *d* due to the fact that the dogs have to move along the channel 26, the curved channel 27 and into the channel 28 and this is sufficient to assure that the next pair of bars *d*, the No. 7 levers, will be in a position to engage the means *g* numbered 70 7 prior to releasing the means *g* numbered 2. Be-

fore, however, pressing the No. 7 buttons, the drawer is released so as to again assume the position shown in Figure 3 by lowering or turning the handle 53. The No. 2 means *g* is secured by the bars No. 2 by the flange portions of said bars engaging the outstanding head portions or the ledge portions 50 and 51 of the means *g*, as shown in Figure 6 at 100. When the No. 7 buttons are pressed inwardly, the No. 7 bars *d* will engage the means *g* shown at 64 and release the means *g* shown at 63, as shown in Figure 7. When the buttons No. 1 are pressed inwardly, the means *g* numbered 7 is released and the means *g* numbered 1 is engaged by the bars *d*, as shown in Figure 8. Thus, card 271 is selected from a group of cards and left suspended above the group, the group of cards being indicated by dotted lines in the several figures at 101.

It will immediately be seen the reason for raising the drawer, although it is evident that instead of raising the drawer, the mechanism for selecting the cards might be lowered to a position where the bars *d* might engage the means *g*. The reason for the raising or lowering, as the case might be, of either the drawer or mechanism just referred to would be so that the first of the means *g* might be engaged. In other words, all cards which started with the figure 2 would be held when the No. 2 buttons were pressed. When the drawer was lowered, said cards starting with the number 2 would be left suspended above all other cards which did not contain such a starting number. Cards having a 2 for the second unit of their number would be suspended also but would be suspended one space lower than those having a 2 for the first unit of their number. Likewise all cards having a 2 for the third unit of their number would be suspended, but would be suspended two spaces lower than those cards whose first unit was a 2. When the No. 7 buttons are pressed, cards having a 7 for the first unit of their number are not held suspended because the means *d* does not engage the tabs of such cards, due to the fact that said cards were slightly lowered immediately after the tabs numbered 2 of such cards were engaged by the pressure of buttons No. 2, as already stated. Cards having a 7 for the third unit of their number are suspended also, but they are suspended one space lower than the cards having a 7 for the second unit of their number, and only if the first or second unit of their numbers were represented by the unit 2. Upon pressing the final number, namely the No. 1 buttons, all cards which ended in 1 and had the first two numbers, namely 2 and 7 would be selected. In this connection, when the No. 1 buttons were pressed, cards having a 1 for the first unit of their numbers are not contacted with by the means *d* because when the No. 2 and the No. 7 buttons were pressed, such cards each time were lowered one space if indeed they were not at that time eliminated entirely due to the fact that they may not have been preceded by a 2 or a 7. Cards having a 1 for the second unit of their number are not contacted with the same reason.

If a card numbered 111 was desired, three of the means *g* would be provided, arranged so that the shanks would extend above one another, or a single shank with three ledges might be provided. It would only be necessary to press one button of the pair at a time, for instance, first the left-hand button No. 1 would be pressed and one of the bars *d* would engage the ledge, the next button would then be pressed and the other bar

would engage the next ascending ledge and upon again pressing the first button, the following ledge would be engaged, thus the card selected. It will be noted that in all probability when the 5 first and also the second buttons No. 1 are pressed in this illustration, that the bars *d* will probably contact with the tabs of cards other than cards representing class No. 111, but that such other cards will be suspended at least one 10 space lower than cards whose number is 111 and, therefore, when the last of the three separate pressures of the No. 1 buttons takes place, the bars *d* will contact with the cards numbered 111 only.

15 The construction of the means *e* is quite important. If a selector button or buttons are pushed inwardly, they are immediately engaged by the member 14 to hold said selector buttons in such inward position. The dogs 42 will slide along 20 the grooves 22 of the means *e* and during this sliding movement, the bar *d* will maintain a certain relative height. However, when the dogs 42 reach the grooves 23, the bars will drop from the first position to a lower position, as shown in 25 Figure 10, it being noted that one of the bars is higher than the other bar, the selector button of the highest bar being in an outward position while the selector button that is pushed inwardly and held by the latch has its bar in a lowered position. This movement allows the cards that have 30 their means *g* in contact with the bar to drop with the result that when the other selector button of a pair is pushed inwardly, the bars will be ready to engage the next head or tab to be selected. In other words, the means *e* is so constructed 35 that the head of the next lower means *g* on the cards is ready to be engaged upon movement of a selector button.

40 After a given card or cards have been selected, the follower block is tightened against the cards, the bars *d* are then released by normalizing the selector buttons by raising the latch 14 by pressing one of the selector buttons partly inwardly whereupon the drawer may be pulled outward 45 from its casing or housing and the selected cards will extend above the top edges of the non-selected cards.

45 The uses of the invention are so numerous that only one or two uses will be designated. In the 50 shoe business, such a device and system would be particularly useful as cards might be provided which would list shoes of a certain size, number, color, and location in a store. If a customer should then call for shoes and the size was 55 double A, 7, light tan, the salesman would press certain of the buttons of the selector system and all cards which would list any said shoes would be immediately selected and the salesman could ascertain by a reading of said cards how many 60 of the shoes of the character desired were in stock and their exact location. If a sale was made from a certain pair of shoes, as listed on certain of the cards, the card or cards could 65 then be sent into the main office and checked off so that a re-order could be sent in or some notation made, after which it would be again filed. This system would likewise be useful in 70 finding broken lines of shoes for the purpose of sales. For instance, a record of the customers might be kept, it being noted on the cards that a certain customer wears a certain size shoe. Regardless of the number of customers, upon 75 pressing the proper buttons having a key or index number, all cards giving the names of cus-

tomers wearing a certain size shoe would be produced.

Another use of this invention would be in the classification of patents. A given classification system would be used which would take the place 80 of the index A shown in Figures 3 and 4, the sub-classes would be given their numbers, and under the sub-classes the different forms of mechanical invention could be listed. Thus, if an application was to be examined for a certain 85 type of pump and if it was desired to find out what had been done by other patentees, it would only be necessary to select the patents of the classification, to group the same and select cards 90 which would indicate the patent references relating to this particular subject matter. In this manner it would be unnecessary for an examiner or patent attorney to attempt to familiarize himself with the different inventions of a given art as a proper selection is a mere mechanical operation. Such a system is also useful in law 95 offices for the classification of clients relative to inventions; for instance, the different classes of inventions, pumps, engines, etc., could be selected and given an index number. Upon pressing the buttons for say, motors, the cards bearing 100 the names of all inventors that had ever invented motors would be produced.

In banks, such a device would be particularly 105 useful, or in fact any place where accounts are kept.

A true cross index is possible with this system since it is evident that the cards can be 110 grouped or filed in visual classes, each group before or behind an ordinary index card, a visual tab indicating that group. My device will choose from any number of groups or classifications one group or class, the individual cards of which might be scattered through the visual classes. 115 In other words, a true cross index is possible whereby each visual class is actually divided 120 mechanically into many classes. For instance, cities of the United States would be separately placed upon cards, which cards would be placed behind a visual tab bearing the name of the 125 State in which the city is located. By this system and with which device, each of the States visually tabbed could be mechanically divided into ten classes based on population and each of 130 these 10 classes could be mechanically divided into ten classes more or less, based upon any data, such as wealth per capita, and in turn these ten classes could, by this device, be divided into a number of other classes based on the 135 amount of bonded indebtedness of each city, etc.

So far as the inventor is aware, this is the only 140 device capable of a true crossing of such a large number of classes in the same cabinet at the same time and with one set of cards where on class is composed of cards belonging and filed at 145 the same time under one or more classes based upon some other viewpoint or consideration.

The inventor is aware that there is a certain 150 system on the market of classifying cards but every card must be touched or moved by a machine prior to the selection of a given card and this renders the operation slow, whereas with this device only the card or cards desired are selected without disturbing the other cards, but probably 155 the greatest benefits can be derived from this device due to the fact that cards may be filed in the usual manner visually by the use of printed tabs or various colored tabs and at the same time, due to the construction of this device and with 160

this system, the same cards may be classified and selected mechanically, although thoroughly crossed and intermingled, and with each of the many mechanically selected classes quickly accessible although the individual cards composing same come from and are intermingled with any or all of the visual classes.

It is obvious that various changes and modifications and variations may be made in practicing the invention in departure from the particular showing of the drawings and the description as given, without departing from the true spirit thereof.

Having thus disclosed my invention, what I claim and desire to secure by Letters Patent is:

1. In a system of the character disclosed, a pair of selector buttons, a pair of selector bars, means to cause approach or separation of said bars upon movement of said selector buttons, and means for locking said selector buttons when said bars are in the position of closest approach.

2. A card-selecting mechanism including a drawer, a case therefor, means for raising and lowering said drawer within said case, and selector means carried by said case and adapted for engagement with cards within said drawer when the drawer is raised to select certain thereof when the drawer is lowered.

3. A card-selecting mechanism including a drawer, cards therein, tabs carried by all of said cards and extending to different heights beyond an edge thereof, a case for said drawer, and selector means carried by the case adapted to engage tabs of different heights for the purpose of segregating selected cards from unselected cards.

4. A card-selecting mechanism including a card, and tabs extending from said card, said tabs on said card each extending to a different distance beyond an edge of said card.

5. A card-selecting mechanism including a file adapted to hold a plurality of cards, a series of index notations on certain of said cards, arranged parallel to one edge, tabs extending from an edge of the cards opposite different ones of said index notations, and selector bars, and means to cause approach of said bars to engage selected tabs representing certain index notations.

6. A card-selecting mechanism including a selector button, a selector bar, means whereby said bar is moved both substantially horizontally and vertically upon movement of the selector button, and means for locking the bar immediately following its vertical movement.

7. A card-selecting mechanism including a pair of selector buttons, a pair of selector bars, means whereby said bars are both moved substantially horizontally and vertically upon joint movement of the selector buttons, and means for locking the bars against further movement immediately following their vertical movement.

8. In a card-selecting mechanism, a pair of selector buttons, a pair of parallel selector bars, means whereby a selector bar is actuated to move both horizontally and vertically relative to the other bar of said pair when one of said buttons is moved, and means for locking the bar so moved after its vertical movement, said bar being released from said locking means when the other selector button and bar of said pair is actuated.

9. A card-selecting mechanism including selector buttons arranged in pairs, pairs of selector bars, means for transmitting movement from each button to a bar, and cam means for each bar whereby upon movement of a bar said bar

is caused to approach to a position midway between the normal positions of the bars.

10. A card-selecting mechanism including a file box adapted to hold a plurality of cards, a series of index notations on certain of said cards arranged parallel to one edge, tabs extending from said edge of the cards opposite different ones of said index notations and selectively placed vertically relative to said card to indicate different orders of classification to which said notations severally apply, selector bars, and means to cause approach of certain of said bars to engage selected tabs representing certain digits.

11. A card-selecting mechanism including a file box adapted to hold a plurality of cards, a series of index notations on certain of said cards arranged parallel to one edge, tabs extending from said edge of the cards opposite different ones of said index notations and selectively placed vertically relative to said card to indicate different orders of classification to which said notations severally apply, selector bars, and means to cause approach of certain of said bars to engage selected tabs representing certain digits, said tabs varying in length whereby when another selector bar is moved, the next longer tab of a selected digit is engaged, the unwanted decimal places of the digit already selected being released.

12. A card-selecting mechanism including a case adapted to hold a plurality of cards, selector bars, means to cause approach and separation of said bars, tabs carried by all of said cards in predetermined positions, said tabs being adapted to be engaged in accordance with movement of certain of said selector bars to suspend the cards carrying said tabs opposite the same, all other cards moving away from said suspended cards.

13. A card-selecting mechanism including a plurality of cards, a series of index notations on certain of said cards arranged parallel to one edge, tabs extending from said edge of said cards opposite different ones of said index notations and to different heights, to indicate decimal places of said index notations, selector bars, and means to cause approach of said bars to indicate a selected tab of a given decimal place and to suspend the cards bearing said tab, all other cards separating therefrom.

14. A card-selecting mechanism including a plurality of cards, a series of index notations on certain of said cards arranged parallel to one edge, tabs extending from said edge of said cards opposite different ones of said index notations and to different heights, to indicate decimal places of said index notations, selector bars, and means to cause approach of said bars to indicate a selected tab of a given decimal place and to suspend the cards bearing said tab, all other cards separating therefrom, further movement of other selector bars engaging further tabs of the suspended cards of different decimal places to hold said cards suspended and reject all unwanted cards from the preselected group.

15. A card-selecting mechanism including selector buttons arranged in pairs, selector bars, and cam means between the selector buttons and selector bars for causing approach or separation of said bars upon simultaneous movement of said selector buttons, said separation occurring after the bars have reached the limit of their approach.

16. A card-selecting mechanism including selector buttons arranged in pairs, selector bars, and cam means between the selector buttons and se-

lector bars for causing approach or separation of said bars upon simultaneous movement of said selector buttons in opposite directions, and latch means for holding said selector buttons, said separation taking place after the bars have reached the limit of their approach.

17. In a card-selecting mechanism, a pair of selector buttons, a pair of substantially parallel selector bars, means whereby a selector bar is actuated to move both horizontally and vertically relative to the other bar of said pair when one of said buttons is moved, and means for locking the bar so moved after its vertical movement; said locking means adapted to be released from said bar when the other selector bar of said pair is actuated, and said first-named means being formed to permit a lag in the movement of the first bar of said pair during its restoration to initial position.

20. 18. A card-selecting mechanism including a case, a drawer therefor, means for raising said cards, selector means carried by said case and adapted for engagement with cards within said drawer when the cards are raised to select and move out of normal alignment certain thereof.

19. A card-selecting mechanism including a case, a drawer therefor, means for raising said cards, selector means carried by said case and

adapted for engagement with cards within said drawer when the cards are raised to select and move out of normal alignment certain thereof, and means adapted to maintain the selected cards out of alignment with the unselected cards.

80

20. A card-selecting mechanism including a drawer, cards therein, tabs carried by all of said cards and extending to different heights beyond an edge thereof, a case for said drawer, means for raising said cards, selector means carried by the case and adapted to engage tabs of a given height on said cards after the cards are raised for the purpose of selecting and moving out of normal alignment certain thereof, and means adapted to maintain the selected cards out of alignment with the unselected cards when said selector means is inoperative.

85

21. In a card-selecting mechanism, a pair of selector buttons, a pair of parallel selector bars, and means whereby a selector bar is actuated from an initial position to move both horizontally and vertically relative to the other bar of said pair when one of said buttons is moved, and to again move to its initial position when the other selector button and associated selector bar is actuated.
